UNITED STATES PATENT OFFICE

FRIEDRICH SCHUMM, OF STUTTGART, GERMANY.

FLOWER-CARD.

SPECIFICATION forming part of Letters Patent No. 508,149, dated November 7, 1893.

Application filed March 10, 1893. Serial No. 465,462. (No model.)

To all whom it may concern:

Be it known that I, FRIEDRICH SCHUMM, merchant, of Stuttgart, Würtemberg, Germany, have invented certain new and useful 5 Improvements in Advertising Cards and Papers, of which the following is a specification.

This invention relates to an improved advertising-card, letter-sheet, bill of fare or similar article, on which artificial flowers are attached in such a manner that the fastening device is not noticeable on the back of the card or sheet, so that the same is adapted for writing or other purposes. Heretofore artificial flowers were attached to cards or sheets 15 or other foundations by means of metallic fasteners, the prongs of which were driven through the paper and clinched on the rear side of the same. This is objectionable for many purposes, when the rear side of the card 20 or sheet is to be used for printing or writing on the same. For the purpose of obviating this objection, the stems of the artificial flowers are attached to a separate piece of stout paper or other suitable fabric, by a metallic 25 fastener, the prongs of which are clinched on the rear side of the piece of paper, which is then pasted or cemented to the foundation card or sheet. The fastening device is formed of metallic clasps, the longitudinal sides of 30 which are provided with downwardly bent flanges or ribs, and the ends of which are provided with tapering prongs passing through the paper, while the side ribs bind on the stem of the flower and retain the same firmly 35 in position on the card or sheet.

In the accompanying drawings, Figure 1 represents a front view of a card or sheet, with an artificial flower attached thereto. Fig. 2 is a vertical transverse section, on the line 2 2 of Fig. 1. Fig. 3 is an enlarged detail sectional view, on the line 3 3, Fig. 1, and Figs. 35 4 and 5 are detailed side and end views of the metallic clasp by which the stem of the flower is attached to the auxiliary fastening plate.

45 Similar letters of reference indicate corresponding parts.

Referring to the drawings, A represents a piece of card-board, letter-sheet, or other foundation of paper, and B an artificial flower 50 with stemmed leaves, which is attached to

the foundation A by a metallic clasp C, the tapering prongs of which are first attached to an auxiliary plate D or piece of stout paper or other suitable fabric. The metallic clasp C is provided with downwardly bent flanges 55 or ribs b' at its longitudinal sides, while the ends are provided with tapering prongs e which are forced through the auxiliary plate D and clinched at the rear of the same. The downward bent flanges or ribs b' are placed 60 across the stem of the flower and are pressed into the same, so that the flower is retained on the piece D in such a manner that the stem can not turn in the clasp. The piece D is provided at its rear side with suitable adhesive substance, and is pasted or cemented to the card or sheet A after the connection of the auxiliary piece D with the stem of the flower is made. 65

The artificial flowers may be scented so 70 that the odor corresponds to the special class of flowers. In this manner, New Year's and birth-day cards, advertising cards, letter-sheets, bills of fare or menus, and similar articles can be ornamented in a very effective, 75 quick and attractive manner, without showing the means of fastening at the back of the card, so that the back can be printed or written on, as desired.

Having thus described my invention, I 80 claim as new, and desire to secure by Letters Patent—

1. The combination, with a foundation card or sheet, of artificial flowers on an auxiliary piece, and a fastening clasp or clip which is 85 attached to the auxiliary piece, so as to retain the stem of the flowers, said auxiliary piece being pasted to the foundation card, substantially as set forth.

2. The combination, of a foundation card 90 or sheet, a sprig of artificial flowers, an auxiliary piece, and a metallic clasp, fastener or clip provided with prongs at the ends, and downwardly bent flanges that extend across the stem of the flowers and fasten the same on 95 the auxiliary piece, which latter is pasted onto the foundation, substantially as set forth.

3. The combination, of a sprig of flowers, with an attaching piece or plate and a metallic fastening clip, the middle portion of which 100

is provided with downwardly bent flanges, and with tapering prongs at the ends, said prongs being clinched at the under side of the piece or plate, which latter is provided with 5 suitable adhesive substance on the under side of same, substantially as set forth.

In testimony that I claim the foregoing as

my invention I have signed my name in presence of two subscribing witnesses.

FRIEDRICH SCHUMM.
